Mr. George F. Moore ATTORNEY.

UNITED STATES PATENT OFFICE.

HARVEY B. BLACK, OF BOGOTA, NEW JERSEY.

GARTER.

1,226,054.

Specification of Letters Patent.

Patented May 15, 1917.

Application filed January 2, 1914. Serial No. 809,898.

To all whom it may concern:

Be it known that I, HARVEY B. BLACK, a citizen of the United States, residing at Bogota, in the county of Bergen and State 5 of New Jersey, have invented certain new and useful Improvements in Garters, of which the following is a full, true, and complete specification.

My invention is an improvement in 10 garters of the kind used in supporting half-hose; and the object is to provide a convenient and comfortable device which permits of adjustment both as to length of the clasp-carrying straps and of the leg-encircling portion, so as to hold the hose snugly 15 and smoothly at two points of support, and which is wholly made of straps and inexpensive metal stampings and so combined as to avoid contact of the metal with the skin.

20 In the drawings:

Figure 1 is a view showing the garter in use;

Fig. 2 is a view of a portion of the garter spread out;

25 Fig. 3 is a section on the line 3—3 of Fig. 2;

Fig. 4 is a perspective view of a slotted plate; and

30 Fig. 5 is a perspective view of a fastening device.

A clasp-carrying tape or strap 6 is provided at each end with any suitable form of hose-supporting clasp 7 such as indicated. This strap is threaded through a slotted 35 plate 8, constituting a direction-changing and adjustment-holding device, from which both ends of the clasp-carrying strap depend in diverging relation, so as to enable the devices 7 to engage the hose at separated 40 points. While the garter may be variously worn, the plate 8 is preferably disposed at the back, the strap ends being carried diagonally forward to engage the hose at opposite sides of the wearer's leg.

45 A portion 9 of the clasp-carrying strap is extended laterally from the plate 8, thus constituting part of the girdle of the garter; and, as shown, this portion is a loop uniting the two strap ends and permitting them to 50 be drawn farther in or out of the plate 8, so as to vary their effective length.

The remainder of the girdle is separate from the clasp-carrying strap and preferably consists of a single strap or tape 10, 55 which is connected at one end to the loop 9 and thence extends around the leg and is

connected to the plate 8. This girdle portion is provided with a separable fastener or catch 11, to enable the garter to be readily applied and removed, and with a take-up device 12, to permit the length of the girdle to be adjusted. This take-up slide also enables the user to compensate for variations in the length of the loop 9, due to adjustment of the lengths of the strap ends 6.

In the particular construction shown the plate 8 is provided with vertical slots 13 and 14, adjacent its opposite ends or sides. It also has downwardly-diverging diagonal slots 15 and 16 in its intermediate portion 70 and a horizontal slot 17 below the diagonal slots. At one end it is provided with an additional vertical slot 18. The separable fastening 11 comprises two members 19 and 20, one of which is carried by the loop 9 and the other by the adjacent end of the girdle strap 10. It is shown of the hook and eye type, but may obviously be of any other suitable character. The member 19 comprises a body plate 21 having two vertical 80 slots 22, 23, with an intermediate bar 24, on which latter is mounted the hook or other fastening element 25.

Following the clasp-carrying strap 6 from its left-hand end in the views, it will be 85 found to pass diagonally upward from beneath through the horizontal slot 17 of the plate 8, over the outer side of the plate, through the diagonal slot 15, behind the plate, outward through the vertical slot 90 13, thence to the right, forming the outer portion of the loop 9, through the slot 22 of the plate 21, behind the bar 24, through the slot 23, thence around the remote edge of this plate, where it is carried backward 95 entirely across the back of the plate, to and across substantially the entirety of the back of the plate 8, forward through the slot 18 and backward through the slot 14 of this plate, behind the plate again, through the 100 diagonal slot 16 and thence downward through the horizontal slot 17, through which both strap ends pass in divergent crossing relation. It will be observed that the clasp-carrying strap 9 thus covers the 105 back of the plate 21 and substantially the whole of the plate 8, so as to keep the metal of these parts from touching the skin. One extremity of the strap 10 is sewed or otherwise secured to the fastening member 20, 110 and the opposite end is looped and passed through the additional vertical slot 18 in

the plate 8, so as to cover the small portion of the underside of the latter not traversed by the strap 9. This extremity of the strap 10 is fastened to the center bar of the take-up slide 12, through the slots of which the strap passes, so that the effective length of the strap can be varied by sliding the device thereon. It will be observed that the back of this plate is also covered by the strap.

10 While I have described the preferred embodiment of my invention with particularity, it will be understood that I am not limited to the precise details shown.

15 What I claim as new is:

1. A garter, comprising a slotted plate, and a clasp-carrying strap threaded therethrough and held in adjustment thereby, said strap having two depending ends, each carrying a clasp, and a looped portion extending laterally from the plate and constituting a part of the girdle of the garter, said looped portion varying in length according to the adjustment of the clasp-carrying strap, in combination with another girdle portion, the same being separate from the clasp-carrying strap and having a separable fastening and a compensating take-up device.

2. A garter, comprising a clasp-carrying strap, and an adjustment-holding and direction-changing device through which the strap is threaded, said strap having two depending ends, each carrying a clasp, and a laterally extending portion forming part of the girdle of the garter, in combination with a separate girdle strap and a take-up device therefor.

3. A garter, comprising a slotted plate, a clasp-carrying strap threaded therethrough and held in adjustment thereby, said strap having two depending ends, each carrying a clasp, and a laterally extending looped portion forming part of the girdle of the garter, in combination with a member of a separable fastening attached to the end of the laterally extending portion, and a separate girdle strap secured at one end to the slotted plate and at the other end carrying the complementary member of the separable fastening and having a take-up to compensate for adjustment of the clasp-carrying strap.

4. In a garter, the combination of a clasp-carrying strap carrying hose supporting clasps at its opposite ends, and a common plate through which the strap is threaded and from which both said ends depend, said plate being provided with two reversely diagonal slots and a horizontal slot which frictionally hold the strap and direct the said ends in diverging diagonal directions.

5. A garter, comprising a slotted-plate, and a clasp-bearing strap threaded through the plate with its ends directed in diverging

relation and provided each with a hose-supporting clasp, said clasp-bearing strap having a laterally extending looped portion, in combination with a separate girdle member which connects with the looped portion.

6. A garter having a slotted plate and a clasp-carrying strap having hose-supporting clasps at its ends, said strap extending upward from one end and threaded through the plate, thence extended laterally and brought back to form a loop constituting part of the girdle of the garter, the back portion of the loop extending substantially entirely across behind the plate, covering the back surface of the same, and being threaded through the plate at the end of said plate remote from the loop and thence passing downwardly to form the other end of the strap.

7. A garter having a slotted plate, and a clasp-carrying strap threaded through and held in adjustment by the plate and having a laterally extended loop forming part of the girdle of the garter, the back portion of the loop extending straight across behind the plate and covering the same and being threaded through the portion of the plate remote from the projecting portion of the loop.

8. A garter having a slotted plate, and a clasp-carrying strap threaded through and held in adjustment by said plate and having a laterally extended loop forming part of the girdle of the garter, the back portion of the loop extending and being threaded through the portion of the plate remote from the projecting portion of the loop across behind the plate and covering the same, in combination with a separate girdle strap secured to the plate at the end of the plate remote from the loop and covering the remainder of the back of this portion of the plate.

9. In a garter, a plate having a vertical slot adjacent each end and downwardly-diverging diagonal slots intermediate of the vertical slots, in combination with a clasp-carrying strap carried by said plate and having its ends passing through the vertical slots, thence through the diagonal slots, whence they extend downward in divergent crossing relation.

10. In a garter, a plate having a vertical slot adjacent each end, downwardly-diverging diagonal slots intermediate of the vertical slots and a horizontal slot below said diagonal slots, in combination with a clasp-carrying strap having its end portions passed through the vertical slots at opposite ends of the plate, thence downward through the diagonal slots, whence both pass through the horizontal slot in divergent crossing relation.

11. In a garter, a plate having a vertical slot adjacent each end, an additional verti-

cal slot adjacent one end, and reversely disposed diagonal slots in its intermediate portion, in combination with a clasp-carrying strap having end portions carrying hose-supporting clasps at their extremities, said end portions passing through vertical slots at opposite ends of the plate, thence through said diagonal slots and downward in divergent relation, an intermediate portion of said strap being formed into a loop extending laterally from said plate, and a separate girdle member secured in the additional vertical slot at the opposite end of the plate and having means of connection with said loop.

12. In a garter, a slotted plate, and a clasp-carrying strap threaded through and held in adjustment by the plate and having ends provided with hose-supporting clasps depending therefrom, said strap having a loop extending laterally from the plate, in combination with a separate girdle strap, one member of a separable fastening carried thereby, and a complementary fastening member carried by said looped portion, said complementary member having a body plate provided with vertical slots and an inter-

mediate bar, the front portion of the loop passing through said slots and beneath the bar and over the outer edge of said body 30 plate and thence backward entirely across the back of this plate, covering the same.

13. In a garter, a slotted plate, and a clasp-carrying strap threaded through and held in adjustment by said plate and having 35 ends provided with hose-supporting clasps depending therefrom, said strap having a loop extending laterally from said plate, and a slide plate carried by the end of said loop, the rear portion of said loop extending 40 entirely across the back of the slide plate, covering the same, and also substantially entirely across the back of the slotted plate, covering the latter, in combination with a girdle member connecting with the slide- 45 plate.

In testimony whereof, I have signed this specification in the presence of two witnesses

HARVEY B. BLACK.
